DEFENSIVE PUBLICATION
UNITED STATES PATENT OFFICE

Published at the request of the applicant or owner in accordance with the Notice of Dec. 16, 1968, 889 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 80 cents a sheet.

Defensive Publication applications have not been examined as to the merits of alleged invention. The Patent Office makes no assertion as to the novelty of the disclosed subject matter.

8 Sheets Drawing. 21 Pages Specification

A large scale data processing system having a high speed low capacity buffer store for buffering data fetch and data store requests to a low speed high capacity interleaved main storage. Requests for storage may come from a plurality of channels which communicate with a storage control unit (SCU) over shared address and data buses. Multiple channel requests are sequenced over this shared bus. The storage control unit controls this sequencing by means of priority circuits and upon granting priority to one of the channels, provides for memory selection. In the case of multiple simultaneous channel requests, the storage control unit unconditionally accepts a request every memory cycle. Upon arrival at the storage control unit, the address and data corresponding to the request are held in registers pending the availability of the requested storage thereby freeing the channel bus for acceptance of another request. The maximum delay that the registered request can encounter is one memory cycle; therefore, the next accepted request will find the register available when it arrives at the storage control unit.
